FISHING LURE

Mary E. Hanna, 721 W. Nevada, Ontario, Calif.

Filed Apr. 20, 1964, Ser. No. 79,611

Term of patent 7 years

(Cl. D31—4)

Fig. 1

Fig. 2

Fig. 3

Fig. 4

FIG. 1 is a perspective view of a fishing lure showing my new design;

FIG. 2 is a side elevational view thereof;

FIG. 3 is also a side elevational view of the same but observing the reverse side; and,

FIG. 4 is a top plan view.

I claim:

The ornamental design for a fishing lure, as shown.
